UNITED STATES PATENT OFFICE.

WILLIAM D. MURRAY, OF PLAINFIELD, AND FREDERICK B. SCHENCK, OF ENGLEWOOD, NEW JERSEY, ASSIGNEES TO THE INTERNATIONAL COMMITTEE OF YOUNG MEN'S CHRISTIAN ASSOCIATIONS, OF NEW YORK, N. Y., A CORPORATION OF NEW YORK.

DESIGN FOR A BADGE OR PENDANT.

No. 37,539.

Specification for Design.

Patented Sept. 12, 1905.

Application filed July 3, 1905. Serial No. 268,288. Term of patent 14 years.

To all whom it may concern:

Be it known that we, WILLIAM D. MURRAY, residing at Plainfield, in the county of Union, and FREDERICK B. SCHENCK, residing at Englewood, in the county of Bergen, State of New Jersey, citizens of the United States, have invented a new, original, and ornamental Design for a Badge or Pendant, of which the following is a specification, reference being had to the accompanying drawing, forming a part thereof.

The figure is a plan of a badge or pendant, showing our new design.

We claim—

The ornamental design for a badge or pendant, as shown.

WM. D. MURRAY.
FREDERICK B. SCHENCK.
